Des. 203,696
Patented Feb. 8, 1966

203,696

DISPENSER FOR PACKAGED PORTIONS OF CONDIMENTS

Ralph G. Page, 6 Hamilton Road, West Peabody, Mass.

Filed Oct. 28, 1964, Ser. No. 82,347

Term of patent 3½ years

(Cl. D52—2)

FIG. 1

FIG. 2

FIG. 3

FIG. 4

FIG. 1 is a front view of a dispenser for packaged portions of condiments, showing my new design.

FIG. 2 is a rear view.

FIG. 3 is a top view.

FIG. 4 is a bottom view.

The dominant features of the design reside in the solid line portions of the drawings.

I claim:

The ornamental design for a dispenser for packaged portions of condiments, as shown and described.
